United States Patent Office

Des. 191,277
Patented Sept. 5, 1961

191,277

PAPER CARTON OPENER

William A. Uttz, 820 Hughes St., Fort Worth, Tex.

Filed July 27, 1960, Ser. No. 61,546

Term of patent 14 years

(Cl. D44—29)

Fig. 1.

Fig. 2.

Fig. 3.

Fig. 4.

Fig. 5.

FIG. 1 is a perspective view of a paper carton opener, showing my new design;

FIG. 2 is a side view thereof;

FIG. 3 is a top view thereof;

FIG. 4 is a rear view thereof; and

FIG. 5 is a front view thereof.

I claim:

The ornamental design for a paper carton opener, substantially as shown.
